(57) **CLAIM**

We claim the ornamental design for a chair, as shown and described.

DESCRIPTION

FIG. 1 is a rear perspective view of a chair.

FIG. 2 is a first side view of the chair of FIG. 1.

FIG. 3 is a second side view of the chair of FIG. 1.

FIG. 4 is a rear view of the chair of FIG. 1.

FIG. 5 is a top view of the chair of FIG. 1; and,

FIG. 6 is a bottom view of the chair of FIG. 1.

The broken lines shown in the drawings are for the purpose of illustrating portions of the chair that form no part of the claimed design.

1 Claim, 6 Drawing Sheets
